(57) **CLAIM**

We claim the ornamental design for a one piece gasket assembly, as shown and described.

DESCRIPTION

FIG. 1 is a plan view from top;

FIG. 2 is a plan view from bottom;

FIG. 3 is a plan view from side; and,

FIG. 4 is a cross sectional view taken along the line 4-4 of FIG. 1.

The broken line showing is included for the purpose of illustrating portions of the article and forms no part of the claimed design.
